Conn., a corporation of Delaware

Application September 17, 1949, Serial No. 116,286

1 Claim. (Cl. 230—123)

1

This invention relates to turbo-jet engines and more specifically to axial flow compressors for such power plants which provide high compression ratios and high mass flow per unit frontal area with relatively low exit velocity.

It is an object of this invention to provide an improved compressor having a plurality of rotors and in which the medium to be compressed is subjected to a compression shock while travelling at supersonic speeds relative to the moving rotor blades with the shocks occurring in the passages formed by the blades.

It is another object of this invention to provide an improved compressor for turbo-jet engines whereby high compression ratios are produced with a minimum of compression stages and a minimum of space.

Another object of this invention resides in the provision of a compressor which exhausts high pressure fluid of such low relative velocity that the diffuser can be completely omitted or reduced to a minimum length.

A further object of this invention is to provide a multiple stage axial flow compressor wherein each stage includes a rotor operating on the shock-in-rotor principle.

Another object of this invention resides in the employment of the self stabilizing inlet phenomenon of a supersonic rotor passage thereby eliminating the necessity of stators between rotors in the compressor.

These and other objects will become readily apparent from the following description of the accompanying drawings in which,

Fig. 1 is a partial cross sectional view of a turbo-jet engine including the compressor forming a part of this invention;

Fig. 2 is a partial cross sectional view illustrating a modified driving means for the compressor rotors;

Fig. 3 is a partial cross sectional view taken along the line 3—3 of Fig. 2;

Fig. 4 is a partially developed view illustrating the compressor rotor and blade arrangement according to this invention;

Fig. 5 is a schematic velocity diagram indicating the velocity relationship of the working fluid and the rotors shown in Fig. 4;

Figs. 5a, 5b and 5c are partial views of the rotor blades illustrating various flow conditions through the blades.

Fig. 5d is a detailed view of a rotor blade indicating in detail the flow through a shock and expansion field; and

Fig. 6 is a diagrammatic illustration of the

2

compressor pressure ratio and efficiency that may be expected of the fluid passing through a shock at various relative inlet Mach numbers.

Although the general practice has been to avoid supersonic relative flow of compressible fluids in compressors due to the high loss expectations, it is known that the supersonic compressors are capable of operating at relatively high compression ratios without exceeding practicable loss limitations. Various types of compressors have utilized the principles wherein supersonic relative flow is obtained in the compressor and the working fluid is passed through a shock to increase the pressure of the fluid and reduce its velocity below that of sound.

Generally speaking, these supersonic compressors are classified as the shock-in-stator type or the shock-in-rotor type. However, in either case it has been the practice to utilize stators or turning vanes to obtain proper operation and fluid flow in the rotors. Since the use of stators entails a certain amount of flow bending, definite losses of various types usually result thereby causing inefficiencies which in addition affect the performance of the rotor blades.

To this end, this invention provides a compressor for a turbo-jet engine which compressor in its preferred form operates on the shock-in-rotor principle but eliminates the usual losses which accompany the use of stators.

Where compression has been achieved by the shock-in-rotor principle, for example, the usual practice has been to utilize turning vanes in the compressor inlet, upstream of the rotor or rotors, to produce proper directional flow and obtain higher relative velocities at the leading edge of the rotor blades. With this type of construction the velocity of the inlet air ahead of the rotors is adversely limited. In other words, depending upon the shape of the turning vanes and the amount of turning produced, local supersonic velocity will readily occur over the vanes as increased subsonic velocities are approached thereby causing separation, possible shock and/or turbulent flow prior to the fluid stream entering the rotor blades. These conditions obviously result in high losses. Such detrimental effects are avoided with this invention to the extent that inlet velocities immediately approaching and exceeding sonic speed can be efficiently handled by the compressor.

Referring to Fig. 1 a turbo-jet engine is generally indicated at 10 having an outer casing 12 and a substantially streamlined inner housing 14 which units cooperate to form an air inlet 16

and an annular passage 18. The inner housing 14 carries two concentric shafts 20 and 22 which are rotatably mounted therein by means of a plurality of bearings 24. An axial flow compressor is provided and includes in its preferred form a pair of adjacent rotors 28 and 30 which are fixed respectively to the shafts 20 and 22. A burner section is provided downstream of the compressor wherein fuel may be injected and the fuel-air mixture ignited to produce an expanding high velocity gaseous medium for rotating the turbine blades 34 and 36 and for further providing a propulsive jet stream in the exit passage 38. The blades 34 and 36 are operatively connected to the shafts 22 and 20 respectively whereby the rear turbine rotor drives the forward compressor rotor 28 and the forward turbine rotor drives the rear compressor rotor 30. The blades 34 and 36 of the adjacent turbine rotors are oppositely inclined relative to the axis of fluid flow so that the shafts 20 and 22 and their respective compressor rotors 28 and 30 are counterrotating. For this reason the compressor rotor blades 50 and 52 will also be oppositely inclined relative to the axis of flow. The principle operation of this compressor will be more fully described hereinafter.

Figs. 2 and 3 indicate a modified drive mechanism for interconnecting the compressor rotors 60 and 62 to the turbine wheel 64. A drive shaft 66 is directly connected to the turbine wheel 64 and the forward compressor rotor 60 while the aft compressor rotor 62 is driven in a direction opposite to that of the rotor 60 by means of a planetary gear system. This gear system comprises an internally toothed ring gear 70 carried by the rotor 62, a plurality of pinion gears 72 which are rotatably mounted in the fixed central housing 76 and a sun gear 78 integral with the drive shaft 66. With this construction, then, a single turbine wheel may be utilized to rotate both compressor rotors in opposite direction. The various components of the planetary system may be varied in size as desired to obtain proper relative speeds between compressor rotors 60 and 62.

Where the rotor blades in each rotor are substantially similar in shape as shown, the rotor 30, for example, will be rotated at a somewhat lower speed than the upstream rotor 28 in order to obtain approximately identical supersonic velocities between the blades of both rotors.

Although the fluid leaving the upstream rotor 28 has an absolute velocity which is less than the absolute inlet velocity it leaves the rotor 28 in a direction such that due to the rotational velocity of rotor 30 it has a relative direction to rotor 30 which is substantially parallel to the chord line of the oncoming blades 52 thereof. Thus the velocity of the fluid entering the rotor 30 is high relative to the moving rotor blades 52 and it is therefore possible to rotate the rotor 30 slower than rotor 28 and still maintain substantially the same supersonic relative velocities through each successive rotor.

It may further be desirable to decrease the pitch of the blades on successive rotors inasmuch as the relative entrance flow to the downstream rotor is more in line with the chord of the approaching blades.

If for certain reasons a higher Mach number were desirable between the rotor blades of the rear rotor 30 than that being obtained through the blading of rotor 28, the aft rotor 30 may be rotated at approximately the same speed. Also,

such identical rotor velocities may be required in the event that the blade structure of each successive rotor varied sufficiently so as to create a different flow velocity through the blades. Thus, for example, should a third oppositely rotating rotor stage be used it would be desirable to have the absolute exit flow from the second rotor to have a direction more in line with the blades of the third rotor rather than in the axial direction shown in Fig. 5.

The utilization of successive counter rotating rotors with supersonic flow between the blade passages also provides a self-compensating effect which insures that the relative flow through the blade passages will continue to move substantially in line with the chord of the blades and thus insure smoothness and proper directional movement of the exit air. This self-compensating effect is best illustrated by referring to Figs. 5a, 5b and 5c which show various conditions of relative flow into the blades of the second rotor.

Fig. 5a shows the relative air entering the blades of the second rotor 30 substantially chordwise of the blades and represents the optimum operating condition of this rotor. Fig. 5b illustrates, in exaggerated form, the direction of relative inlet flow when the fluid approaching the blades 52 is such that the blades are at a negative angle of attack. As the flow enters the blade passages an expansion field is generated at the leading edge of the blades adjacent the face thereof. In moving through the expansion field the air flow is deflected toward the face of the blades as shown so that it subsequently flows substantially parallel to the face of the blades. At the same time an oblique shock will be produced near the leading edge on the backside of the blade and the fluid flowing through this shock will also be deflected so that the flow will continue downstream substantially parallel to the chord of the blades. The bending of flow through the expansion field and the shock is more clearly shown in detail in Fig. 5d.

Referring to Fig. 5c a condition of flow opposite to the Fig. 5b situation is shown wherein the relative inlet flow to the rotor is such that the approaching rotor blades are relatively at a high positive angle of attack. Under this condition an expansion field will be produced near the leading edge and on the backside of each blade while a shock will be generated adjacent the face of each blade to deflect the flow. Conditions shown in Figs. 5b and 5c will tend to decelerate and accelerate the inlet axial flow respectively so as to approach condition shown in Fig. 5a. Under all the foregoing flow conditions the blade passages will still generate a normal shock downstream in the vicinity of the diverging portion of the passages.

It is to be understood that the same conditions may exist at the blade entrance of the first rotor. It is then apparent that with the self-stabilizing effect that the use of stators or turning vanes can be completely eliminated.

Fig. 6 illustrates the comparison of theoretical pressure ratio and efficiency at various Mach numbers that may occur when a fluid passes through a normal shock which stabilizes in the blades passages of a supersonic compressor. A similar comparative chart may be used as a criterion for choosing design proportions. It will be noted that for example a pressure ratio of 3 is obtainable in each stage with an efficiency approximately 80 percent and this pressure ratio may be further increased at higher Mach num-

bers with a corresponding decrease in efficiency. However, even with some loss of efficiency, at increased Mach numbers within the rotors, extremely high compression ratios are available thereby permitting extremely high power output in a turbo-jet engine and the like. It is further apparent that with one stage producing a compression ratio of 3 the introduction of a second stage of similar theoretical efficiency and without having the normal losses usually encountered with stators, an overall compression ratio of 9 could readily be produced. A compressor of the type described would normally be designed for operation in a region between the lines A and B which are superimposed on the chart of Fig. 6. In other words, the shape of the blades, the size of the blades, the spacing of the rotors and the rotational velocity of the rotors would be of such values that most efficient operation would be obtained for example in the Mach number range between the lines A and B to thereby produce the corresponding compression ratios and efficiencies. The compression ratios and efficiencies illustrated in Fig. 6 are by way of example only and are not limiting ranges of this invention.

The axial spacing of the rotors of the compressor of this invention may be increased somewhat to permit pressure bleed-off and stabilization of flow conditions during starting and off-design operation. Also the hub tip ratios of the compressor may be altered to obtain optimum passage flow conditions and radial equilibrium.

It is therefore apparent that as a result of this invention it is possible to obtain a very high pressure rise across each compressor rotor thereby providing a high pressure operating unit having a high mass flow capacity with minimum space and weight requirements. Such high pressure and high mass flow capacities permit a turbo-jet engine or the like to operate at unusually high power output with the possible expense of some losses which are, however, within a practicable limit.

Further, as a result of this invention it is apparent that a high capacity compressor has been provided which is readily adaptable to a greater number of stages than that illustrated.

It is also apparent that as a result of this invention a compressor and power plant is provided which is readily adaptable for aircraft inasmuch as the counterrotating compressor and turbine rotors produce no gyroscopic forces during aircraft maneuvers.

Although certain embodiments of this invention have been illustrated and described herein, it is apparent that various modifications and changes may be made in the arrangement and construction of the various parts without departing from the scope of this novel concept.

What it is desired to obtain by Letters Patent is:

15 A compressor comprising a casing structure having an annular substantially unobstructed airflow passage, a plurality of compressor rotors journaled axially in said casing structure, blading carried by each of said rotors and extending 20 across said passage, means for rotating each successive downstream rotor at proportionally lower rotational speed and in a direction opposite to its preceding rotor, said blades having a thickness which reduces toward their trailing edges for at 25 least a distance from mid-chord to said trailing edges thereby forming diverging passages therebetween so as to impart a normal shock to the gaseous medium entering said blades to provide an immediate reduction in the velocity of said medium relative to said rotor blades and thereby effecting an immediate increase in pressure of said medium.
